FIG. 1

FIG. 2

FIG. 3

FIG. 5

FIG. 4

FIG. 1 is a front elevational view of the combined electric fuse body and integral handle showing my new design;

FIG. 2 is an end elevational view thereof;

FIG. 3 is a top plan view thereof;

;

FIG. 4 is a bottom plan view thereof; and

FIG. 5 is a fragmentary cross-sectional view of the handle taken along line 5-5 of FIG. 1.

The characteristic feature of my design resides in the specific configuration of the handle portion.

I claim:

The ornamental design for a combined electric fuse body and integral handle, as shown and described.
